L.L.P.(57) **CLAIM**The ornamental design for a garment, as shown and
described.**DESCRIPTION**FIG. 1 is a front left perspective view of a garment showing
my new design in an in-use configuration;

FIG. 2 is a front view thereof;

FIG. 3 is a rear view thereof;

FIG. 4 is a first side view thereof; and,

FIG. 5 is a second side view thereof.

The evenly-spaced broken lines shown in the drawings are
directed to environment and form no part of the claimed
design.The dash dot broken lines depict boundaries of the claim that
form no part of the claim.The contrast shading represents a contrast in appearance
only.**1 Claim, 5 Drawing Sheets**FIG. 1
